[57] CLAIM

The ornamental design of a boat hull, as shown.

DESCRIPTION

FIG. 1 is a perspective view looking aft from above the starboard bow of a boat hull showing my new design;

FIG. 2 is a top plan view thereof;

FIG. 3 is a bottom plan view thereof;

FIG. 4 is a port side elevation view thereof;

FIG. 5 is a starboard side elevation view thereof;

FIG. 6 is a front perspective view thereof; and

FIG. 7 is an oversize rear perspective view thereof.

FIG. 8 is a fragmentary representation of the starboard aft corner of a boat hull in accordance with my new design, as viewed from the bottom side of said corner.
